EDWIN G. BUSSE, OF CHICAGO, ILLINOIS, ASSIGNOR, BY MESNE ASSIGNMENTS, TO
FREDERIC SCHAEFER, OF PITTSBURGH, PENNSYLVANIA

BRAKE BEAM HANGER BRACKET

Application filed May 4, 1927. Serial No. 188,685.

My invention relates to railway rolling stock and consists in an improved mounting for brake beam hangers. It has long been the practice to form the brake beam hangers of rod material provided with eyes at the upper ends for engaging hanger supporting pins. Obviously such support affords substantially a point contact between the hanger and the pin and there is a minimum amount of metal to resist wear. Consequently, such wear took place before the hangers were in use for any considerable length of time and this would result in lowering the hanger and beam.

15 To prevent this condition, the hangers have been formed in the shape of a closed loop with a relatively long section swinging on a corresponding supporting surface, and recently the American Railway Association 20 has specified such construction.

The object of my invention is to provide an improved bracket for such a hanger by utilizing a removable bushing which may be replaced when excessive wear has taken 25 place. The use of such a bushing has been previously suggested but so far as I am aware such bushings have always been so assembled with the bracket on which they were mounted with the hanger which they support that it was impossible to remove the hanger without also removing the bushing, and it is a further object of my invention to produce a renewable bushing which will permit the brake hanger to be removed without 30 necessarily disassembling the bushing from its bracket.

In the preferred form of my invention I attain a still further object, namely, that of preventing the removal of the hanger from 40 the bushing and bracket unless the hanger is rotated to an abnormal position, such as would not be assumed at any time during the functioning of the hanger.

In the accompanying drawings which 45 illustrate my invention—

Figure 1 is an elevation of the side of a truck side frame provided with a bracket for a brake beam hanger and showing the application of my bushing and a hanger supported 50 thereby.

Figure 2 is an enlarged detail vertical section through the bracket, bushing, and hanger.

Figure 3 is a vertical transverse section on line 3—3 of Figure 2.

Figures 2 and 3 illustrate the preferred 55 embodiment of my invention.

Figures 4 and 5 are, respectively, side views and end views of a bracket and associated parts and illustrate a modification of 60 my invention.

Figures 6 and 7 similarly illustrate another modification of my invention.

Figures 8 and 9 similarly illustrate another 65 modification of my invention.

Figures 10 and 11 illustrate still another modification of my invention.

Figures 12 and 13 illustrate another modification of my invention.

Figure 14 indicates the general shape of 70 all the forms of the bushing before the same is assembled with the bracket.

In the underframe structure illustrated in Figures 1, 2, and 3, the truck side frame 1 is shown as comprising a one-piece casting 75 including an integral bracket 2 having spaced jaws 3 and 4 forming an open-ended recess with an open side. Seated in this recess is an open-ended and open-sided bushing 5 substantially U-shaped in cross section. 80 Lugs 6 on the jaws 3 and 4 and corresponding projections in the legs of bushing 5 form interengaging elements which resist movement of the bushing out of the recess formed by the jaws. Bushing 5 is preferably formed 85 of yielding material with diverging legs as shown in Figure 14, and the legs are compressed when the bushing is inserted between jaws 3 and 4 whereby the elasticity of the bushing causes its legs to engage with the 90 lugs 6 on the jaws. The ends of bushing 5 are flanged outwardly as indicated at 7 whereby the bushing is more securely retained in the recess and the edges of jaws 3 and 4 are protected against wear from frictional contact with the hanger 8.

The depressed portions 9 of the bushing legs approach each other to form a restricted 95 passage between the hanger seat at the inner end of the bushing and the open side of the 100

bushing. The upper portion of hanger 8 which is seated in the bushing is preferably formed of a flattened or ovoid cross section, the longer axis of which is greater than the 5 width of the restricted passage formed by depressions 9, but the shorter axis of which will permit the hanger to be removed from the bushing when the hanger is rotated to the dot-and-dash position indicated at 10. 10 It will be understood that this dot-and-dash position is one which the hanger cannot assume while it is supporting the brake beam in the usual manner. If the diameter of the 15 bar is no greater than the distance between depressions 9, it will be seen that the hanger may be removed through the end of the bushing as well as through the side of the bushing.

As an additional precautionary measure, 20 a pin 11 may be inserted through jaws 3 and 4 and bushing 5.

It will be seen that upon removal of pin 11, if the latter is used, the hanger may be removed from the bracket without disturbing 25 the bushing. Hence there will be little likelihood of the bushing being misplaced during adjustment or repairs on the brake beam or other parts.

If at any time, however, the bushing is 30 unduly worn, the same may be easily removed and replaced with a new bushing. In this form of my invention, it will be noted that the bushing may be reversed top for bottom and its life thereby increased.

35 In the structure illustrated in Figures 4 and 5, the bushing 12 is provided with lugs 13 which extend into suitable depressions in jaws 14 and the ends of the bushing do not have the flanges provided on the bushing 40 illustrated in my preferred form. With this mounting the hanger can be removed from the bushing without rotating it from its normal position and this may be found desirable in some applications. The locking pin 15 may be used or not as desired.

50 In the modification illustrated in Figures 6 and 7 the legs of the bushing 16 are seated in a depression formed in the jaws 17 and suitable lips 18 on the latter retain the bushing. With this form of the bushing and jaw it will be necessary to remove the bushing endwise rather than through the open side of the jaw. The hanger 19, however, may be rotated and removed through the open side or 55 end of the jaw without removing the bushing.

In the modification illustrated in Figures 8 and 9, the legs of bushing 20 are straight and are seated in depressions in the jaws and 60 at their ends are provided with flanges 21 which engage the outer faces of the jaws near the open side of the recess.

In the modification illustrated in Figures 10 and 11 the bushing 22 also has straight 65 legs engaged by suitable lips 23 on the ends

of the jaws. This construction is perhaps the simplest form of my invention.

In Figures 12 and 13 the bushing 24 is provided with projections 25 which resist movement of the bushing lengthwise of the 70 recess between jaws 26 but do not resist movement of the bushing through the open side of the recess between the jaws, such movement being resisted by the engagement of the lips 75 27 with the ends of the legs of the bushing.

In each of the modified forms of my invention, one or more features of the preferred embodiment are retained, and all of the forms attain the general object of my invention, namely, the provision of a renewable 80 bushing which is not necessarily disassembled with the bracket when the brake hanger is removed from the bracket.

Obviously many other modifications in the 85 detailed structure of the bushing may be made without departing from the spirit of my invention, and I contemplate the exclusive use of such variations as fall within the scope of my claims.

I claim:

1. In a brake beam hanger bracket, members forming an open-ended and open-sided recess, and an open-ended bushing in said recess with an open side and formed of spring material, the elasticity of said bushing retaining it in said recess. 95

2. In a brake beam hanger bracket, members forming an open-ended and open-sided recess, and an open-ended bushing in said recess with an open side and formed of 100 spring material, there being elements on said bushing and the side of said recess adapted to be interengaged by the elasticity of said bushing, when the latter is seated in said recess, to positively resist movement of said bushing out of said recess. 105

3. In a brake beam hanger bracket, members forming an open-ended and open-sided recess, an open-sided bushing of spring material seated in said recess, said bushing and the side of said recess having depressed and projecting elements caused to interengage by the elasticity of said bushing to resist movement of said bushing in said recess, and means for holding said bushing against movement irrespective of said elements. 110

4. In a brake beam hanger bracket, members forming an open-ended and open-sided recess, a renewable bushing seated in said recess, movable through the open side thereof and having flanged ends engaging the outer faces of said members at the ends of said recess, there being interengaging elements on said bushing and the sides of said recess for resisting movement of said bushing through the open side of said recess, said bushing being compressible to free said elements from each other. 120

5. In combination, a brake beam hanger bracket having an open-ended and open-sided 130

- recess, a renewable U-shaped bushing in said recess, a hanger mounted in said bushing, and a hanger retaining element passing through said bracket and bushing and removable from said bracket independently of said bushing. 5 of the slot and its outer end engaging the inwardly projecting detent at the end of the slot.
6. In combination, a brake beam hanger bracket having an open-ended and open-sided recess, a renewable U-shaped bushing in said recess, a hanger mounted in said bushing, and a retaining element for said bushing and hanger removable therefrom without disturbing said bushing and hanger. 10 70
10. In combination, a brake beam hanger bracket having an open-ended and open-sided recess, a renewable U-shaped bushing in said recess, a hanger mounted in said bushing, and a retaining element for said bushing and hanger removable therefrom without disturbing said bushing and hanger. 15 75
15. In combination, a brake beam hanger bracket having an open-ended and open-sided recess, a renewable U-shaped bushing in said recess removable through the open side thereof, a hanger mounted in said bushing, and a removable pin passing through said bracket 20 across the open side of said recess. 80
20. In combination, a brake beam hanger bracket having an open-ended recess with an open side, a hanger bushing in said recess, and elements on said bracket and bushing 25 for automatically interlocking when the bracket and bushing are assembled. 85
25. In a brake beam hanger bracket, members forming a recess, a hanger supporting bushing bodily seated in said recess and 30 adapted to be removed and reversed to provide a different hanger engaging surface, and elements on said members and bushing automatically interengaging to hold said bushing in place when said bushing is assembled 35 with said members. 90
35. In a brake beam hanger bracket, members forming a recess, a hanger supporting bushing bodily seated in said recess and 40 adapted to be removed and reversed to provide a different hanger engaging surface, and elements on said members and bushing automatically interengaging to hold said bushing in place when said bushing is assembled 45 with said members. 95
40. The combination of a truck frame for railway cars provided with a bracket having an open ended slot for receiving a brake hanger, and a bushing of resilient wear-resisting metal adapted to be fitted in said slot, said bushing and the wall of said slot being provided with cooperating interlocking detents permitting said bushing to be snapped into place and thereafter holding it in its 45 operative position. 100
45. The combination of truck frame for railway cars provided with a bracket having an open ended slot for receiving a brake hanger, and a substantially U-shaped bushing of resilient wear-resisting metal adapted to be fitted in said slot with its base adjacent the inner end of the slot, said bushing and the wall of said slot being provided with cooperating interlocking detents permitting said bushing to be snapped into place and thereafter holding it in its operative position. 110
50. The combination of truck frame for railway cars provided with a bracket having an open ended slot for receiving a brake hanger, and a substantially U-shaped bushing of resilient wear-resisting metal arranged in said slot with its sides 55 pressing yieldingly against the inner surface 115
55. The combination of truck frame for railway cars provided with a bracket having an open ended slot for receiving a brake hanger and having an inwardly projecting detent partially closing the opening in the outer end of the slot, and a substantially U-shaped bushing of resilient wear-resisting metal arranged in said slot with its sides 60 65 120
60. The combination of truck frame for railway cars provided with a bracket having an open ended slot for receiving a brake hanger and having an inwardly projecting detent partially closing the opening in the outer end of the slot, and a substantially U-shaped bushing of resilient wear-resisting metal arranged in said slot with its sides 65 70 75 80
65. The combination of a truck frame for railway cars provided with a bracket having an open ended slot for receiving the brake hanger, and an open ended bushing of resilient wear-resisting metal adapted to be arranged in said slot, said bushing being provided with flanges engaging the sides of said bracket to prevent transverse movement of the bushing in the slot, and said slot and the wall of said bushing being provided with cooperating interlocking detents permitting said bushing to be snapped into place and thereafter retaining it in its operative position. 85
